UNITED STATES PATENT OFFICE.

OTTO THOST, OF ZWICKAU, GERMANY.

DESIGN FOR A GRATE-BAR.

SPECIFICATION forming part of Design No. 30,505, dated April 4, 1899.

Application filed February 25, 1899. Serial No. 706,888. Term of patent 14 years.

To all whom it may concern:

Be it known that I, OTTO THOST, a subject of the King of Saxony, and a resident of Zwickau, in the Kingdom of Saxony, German Empire, have invented and produced a new and original Design for Grate-Bars, of which the following is a specification, reference being had to the accompanying drawings, forming a part thereof.

The accompanying drawings represent the design which embodies my invention.

The leading feature of my design consists in a grate-bar which comprises an undulated center portion having downward grooves which gradually decrease, ending in a narrow straight lower edge. On either side the bar has somewhat broader supports with lugs.

The drawings illustrate a grate-bar, in which 1 represents a serpentine-shaped center portion, Figure 1. 2 are the supports, and 3 represents a lug located directly at the extreme

end. 4 shows lugs located between the serpentine center portion and the extreme end, and 5 represents the gradually-disappearing grooves. The lugs and the supports are practically rectangular, Figs. 1 and 2, while the main center portion gradually diminishes in size from the serpentine-shaped top down to the straight bottom edge, Fig. 3. Two bars laid together show the serpentine lines to be 30 parallel, Fig. 1.

Having thus described my invention, I claim—

The design for a grate-bar substantially as shown and described.

In testimony whereof I affix my signature in the presence of two subscribing witnesses.

OTTO THOST. [L. s.]
